SAFETY PORTABLE BOAT

Filed May 21, 1923

UNITED STATES PATENT OFFICE.

MARIANO PIMPINELLA, OF AMBLER, PENNSYLVANIA.

SAFETY PORTABLE BOAT.

Application filed May 21, 1923. Serial No. 640,292.

To all whom it may concern:

Be it known that I, MARIANO PIMPINELLA, a subject of the King of Italy, residing at Ambler, in the county of Montgomery and 5 State of Pennsylvania, have invented certain new and useful Improvements in Safety Portable Boats, of which the following is a specification.

This invention relates to boats, having 10 more particular reference to small boats for private use on inland waters, the invention being capable of embodiment either in manually propelled, or power driven boats.

The invention has for an object the provision 15 of a novel type of knock down or portable boat, which can be readily separated into sections for convenience in transportation, a further object relating to the provision of a novel balancing means.

20 For further comprehension of the invention, and of the objects and advantages thereof, reference will be had to the following description and accompanying drawings, and to the appended claims in which the 25 various novel features of the invention are more particularly set forth.

Fig. 1 of the drawings is a side view of a boat having the invention applied thereto.

Fig. 2 is a plan view thereof.

30 Fig. 3 is an enlarged fragmentary transverse section taken on the line 3—3 of Fig. 2 and showing particularly the balancing float and the means for swinging it down to operative position.

35 Fig. 4 is a fragmentary sectional view of this float swinging means.

Fig. 5 is a detail sectional view showing a means for securing the hull sections together.

40 As here shown my improved boat has its hull divided into a front section 10, and intermediate section 11, and a rear section 12. These sections present transverse partition elements such as 13 at their abutting 45 ends so that each section forms a separate water tight compartment and not being dependent on its connection with the other section to prevent ingress of water. The respective sections may be suitably joined 50 together by means permitting of ready detachment. As shown in Fig. 5, I may provide bolts such as 15 which are fixed in the transverse partition of one section and project through suitable openings in the 55 adjacent partition of the other section and have nuts such as 16 threaded on their ends,

rubber washers such as 17 being interposed to prevent leakage. The forward and intermediate sections may have rearwardly projecting flange elements such as 18 which engage over the forward edges of the intermediate and rear sections respectively. 60

The intermediate section may be formed with the usual cockpit 20 for accommodation of the passengers. I have here shown the 65 invention as applied to a motor boat provided with a small motor 21 which drives a propeller 22, these parts being carried by the intermediate section 11. It will be understood of course that the invention can 70 be also applied to a rowboat.

To assist in balancing the boat I provide a pair of balancing floats 25 which are in the form of elongated chambered members having curved undersides to engage the 75 water. These floats are hinged to the sides of the section 11 as indicated at 26, the hinge pintles being readily removable, and they remain normally in the raised position 80 clear of the water indicated in dotted lines in Fig. 3, being held in this position by means of springs such as 28 coiled around the hinge pintles of the floats and bearing at one end on the latter and on the opposite end on the side of the boat. 85

I preferably provide means whereby these floats can be readily swung down to engage the water, and this means comprises for each float longitudinally expansible thrust bar which is connected at one end to the 90 section 11 and at its other end to the float near the outer side of the latter. This thrust bar comprises a series of tubular sections 95 30 which telescope one into the other and are provided with cooperating flange elements 31 to prevent displacement from each other, one end section being pivotally connected to a bracket 32 removably bolted to the float. The other end section is in the form of a T-member 30' whose cross-piece is pivotally engaged in a bracket 34 fixed to the side of the boat section 11. Leading through one side of this bracket and into the T-member 30', is a passage 35 to the outer end of which a short length 100 of flexible tubing 36 is removably connected this tubing leading from a pipe 37, leading in turn from a tank 38 which contains compressed air. Upon the pipe is a valve 39 provided with a hand lever 40 for quick 105 operation.

In the event of the boat tilting danger-

ously to one side, the operator opens the valve 40 on that side, allowing the air to flow from the tank 38 into the thrust bar 30 and cause the latter to expand, swinging 5 the float 25 down to the position shown in full lines in Fig. 3 in which it engages the water. Leading from the T-head 30' through the bracket 34 is a minute passage 42 which allows of gradual escape of the air 10 so that the float automatically rises slowly to its elevated position. This passage may be closed when desired by a screw plug 43.

As will be apparent, I have provided a novel and improved type of boat which is 15 convenient for transportation when necessary and which affords adequate safety without the need of being made of any great width of beam.

Having thus described my invention, what 20 I claim as new and desire to protect by Letters Patent of the United States is as follows:

1. In a boat, a float hinged to the side thereof, means normally holding said float 25 above the water level and means for swinging said float downward to engage the water, said last means comprising a longitudinally expansible thrust bar, consisting of a number of telescopic tubular sections, and means 30 for supplying compressed air to the interior of said thrust bar.

2. In a boat, a float hinged to the side thereof, means normally holding said float

above the water level and means for swinging said float downward to engage the water, 35 said last means comprising a longitudinally expansible thrust bar, consisting of a number of telescopic tubular sections, and means for supplying compressed air to the interior of said thrust bar, the upper end of said 40 bar being in the form of a T-head, a bracket fixed to the side of the boat in which said T-head is pivoted, said bracket having a passage formed therein for the introduction of air to the said expansible 45 bar, and a pipe leading from a supply of compressed air and connected to said passage.

3. In a boat, a float hinged to the side thereof, means normally holding said float 50 above the water level and means for swinging said float downward to engage the water, said last means comprising a longitudinally expansible thrust bar, consisting of a number of telescopic tubular sections, and means for supplying compressed air to the interior of said thrust bar, a 55 spring normally urging said float upward, and means providing a minute vent from said thrust bar to permit of the float gradually moving upward under the influence of said spring.

In testimony whereof I have affixed my signature.

MARIANO PIMPINELLA.
